BY

ATTORNEY

UNITED STATES PATENT OFFICE.

ERVE C. STRICKLAND, OF SAN JOSE, CALIFORNIA.

ELECTRIC HEATER.

Application filed February 9, 1922. Serial No. 585,844.

To all whom it may concern:

Be it known that I, ERVE C. STRICKLAND, a citizen of the United States, and resident of San Jose, in the county of Santa Clara and State of California, have invented a certain new and useful Improvement in Electric Heaters, of which the following is a specification.

My invention relates particularly to an electric heater adapted to be used in combination with pleating irons such as are used in laundries.

It is an object of my invention to provide a heater of the character indicated which can be plugged into the regular electric light systems and which is so constructed as to use a minimum amount of current consumption for the heat required. Also the device is so constructed as to be easy to manufacture, simple in operation, and serve as a stand and holder for the pleating irons when not being used.

It is also an object to provide a heater which will prevent the over heating of the irons and the consequent scorching of the materials to be pleated.

In the drawing:—

Figure 1 is a front elevation of the heater.

Figure 2 is a side elevation of the same showing the ventilating orifices as well as a pleating iron in place on the iron holder.

Figure 3 is a plan view of the heater.

Figure 4 is a cross-section on line 4—4 of Figure 2 showing a pleating iron in position for heating.

Referring more particularly to the drawings, I show a sheet metal container having two sides as 1—2, a bottom and top as 3—4 and the front and back as 5—6 respectively. The whole being formed as shown and mounted upon supporting members 7.

Sides 1—2 have suitable orifices as 9—9—9—9 and openings 10—10 which act as ventilators for the heating elements 11—11—11. Said heating elements are formed of insulating and heat resisting material such as porcelain, with collars 12—12—12 extending outwardly therefrom at one end. The inner openings 13—13—13 of said heating elements are of sufficient size as to allow the entrance of the largest size pleating irons used as shown at 14. Heating elements 11—11—11 are inserted through

suitable openings in the front side 5, the collars 12—12—12 holding the same in position. These elements are wound with suitable resistance wire as 15 and are connected in series as shown, the two leads 16—17 being connected to standard plug terminals 18—19 which are insulated from and pass through suitable openings in the back 6 of said container.

The front 5 of the container is extended a distance above the top as shown at 20 and has grooves 21—21—21 cut therein to receive the pleating irons when not in use as shown in Figure 2, said grooves 21—21—21 being on a line with the openings 13—13—13 of heating elements 11—11—11.

The operation of the device being as follows:—

The plug elements 18—19 being connected to the electrical circuit through the medium of the standard cord and plug such as is used on electric irons, which is not shown, the current passes thru wire 16, resistance wires 15—15—15 and wire 17 thus heating the said resistance coils. This heat is taken up by the pleating irons which are placed in openings 13—13—13, the container being cooled by means of ventilating orifices 9—9—9 and openings 10—10 in the sides 1—2. If it is desired to use only one iron and the other two are already heated the same can be removed from the heating element and placed in grooves 21—21 on the top of the container. The heat radiation from the elements and from the top of the container is sufficient to hold the heat of the irons placed thereon for a considerable length of time. Thus it can be seen that the irons can be kept hot and yet all danger from excessive overheating is avoided by the proper use of the device.

It is to be understood, of course, that while I have herein shown and described one particular embodiment of my invention, that changes in form and construction may be made within the scope of the appended claim.

I claim:—

A device of the character indicated comprising a stand of heat conducting material having a closed top and ventilating means arranged in the upper part of its side portions, a plurality of tubular elements ar-

ranged in a horizontal plane within said stand, each tube having an open end communicating with the front of said stand whereby to receive pleating irons, and heating 5 elements wound around said tubes and operatively arranged in an electrical circuit, the front of said stand extending a distance

above the top thereof and having a plurality of notches formed therein adapted to receive and support the handle end of the 10 pleating irons when not in use or in said tubes.

ERVE C. STRICKLAND.
